US0D1063068S

(12) **United States Design Patent** (10) **Patent No.:** **US D1,063,068 S**
(45) **Date of Patent:** **** Feb. 18, 2025**

(54) **INJECTION DEVICE**

- (71) Applicant: **Novo Nordisk A/S**, Bagsværd (DK)
- (72) Inventors: **Signe Utoft Andersen**, Copenhagen (DK); **Lee Higson**, Tisvilde (DK); **Luca Corvatta**, London (GB); **Sam Hecht**, London (GB); **Kimberlee Colin**, London (GB)
- (73) Assignee: **Novo Nordisk A/S**, Bagsværd (DK)
- (**) Term: **15 Years**
- (21) Appl. No.: **29/837,464**
- (22) Filed: **May 5, 2022**

Related U.S. Application Data

- (63) Continuation of application No. 29/797,177, filed on Jun. 29, 2021, now Pat. No. Des. 955,567, which is a continuation of application No. 29/704,548, filed on Sep. 5, 2019, now Pat. No. Des. 926,973.

(57) **CLAIM**

The ornamental design for an injection device as shown and described.

DESCRIPTION

FIG. 1 is a perspective view of an injection device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the injection device which form no part of the claimed design.
